UNITED STATES PATENT OFFICE

LOUIS A. PARADISE, OF MOLINE, ILLINOIS, ASSIGNOR TO DEERE & COMPANY, OF MOLINE, ILLINOIS, A CORPORATION OF ILLINOIS

CONVEYER

Application filed October 21, 1925. Serial No. 63,837.

My invention relates to conveyers such as are commonly used on threshers, corn pickers, and the like. Such conveyers usually are composed of a pair of endless chains spaced 5 apart and operating over sprocket wheels mounted on shafts at each end of the conveyer, the chains being cross-connected at intervals by wooden slats the ends of which are connected to links of the chain. In machines 10 of the type referred to, the conveyer is usually associated with a table or chute along the upper surface of which the slats travel, the product being conveyed being supported by the table as it is moved along by the slats. 15 The distance apart at which the slats are set varies in different machines, and in cases where the slats should be close together each link of the conveyer chains may have a slat secured to it, but usually the slats are disposed farther apart than the length of the 20 links, and in such instances the chains are generally composed of links of different types, some being standard links while others are designed especially for connection there- 25 with of the ends of the slats. The general practice is to secure the slats to such links by rivets, and with that construction the power transmitted to the slats by the chain for moving the product that is being conveyed is ap- 30 plied directly through the rivets; conse- quently, in cases where a slat is subjected to unusual strain by reason of carrying an extra heavy load, or because of resistance to the 35 progress of the load, the rivet is apt to split the slat. If this should occur and a part of the slat should become loose, it may pass along with the product being conveyed and into the mechanism with which the conveyer may be associated. For example, in the case 40 of a threshing machine the broken slat may pass into the thresher cylinder and cause considerable damage. It is therefore highly desirable that in conveyers of this type the cross- 45 slats be so connected with the chains as to materially reduce, if not eliminate, the danger of such accidents, and the object of my present invention is to provide a construction which will accomplish that end. I achieve 50 this object as illustrated in the drawings and

as hereinafter described. What I regard as new is set forth in the claims.

In the accompanying drawings:—

Fig. 1 is a plan view showing part of one of the conveyer chains with part of one of the 55 cross-slats secured thereto;

Fig. 2 is a vertical section on line 2—2 of Fig. 1; and

Fig. 3 is a perspective view illustrating my improved chain link which forms the means 60 of attaching the slat to the chain.

Referring to the drawings,—4 indicates the ordinary links of a conveyer chain, which links may be of any standard design, and 5 indicates my improved link which is of the special design hereinafter described. In Figs. 1 and 2 of the drawings I have shown part of a conveyer chain made up of one of the links 5 connected up with several standard links 4, but it will be understood that if desired the chain may be composed entirely of my improved links, or such links may be spaced a greater or less distance apart as circumstances may make advisable.

My improved link comprises a driving element composed of two approximately parallel members 6, 7 connected at one end by a tubular cross-member 8 the bore of which is indicated by the reference numeral 9, as shown in Fig. 3. That end of the link at 75 which the tubular member 8 is located is adapted to fit between the side members of the next adjoining link of the chain, as shown for example in Fig. 1, in which it fits between the side members 10, 11 of one of the links 80 4. The bore 9 is adapted to receive a link pin 12 which passes therethrough and through suitable holes in the ends of the members 10, 11 in the usual way. Preferably an oil hole 13 is provided for the admission of 85 oil to the pin 12, as shown in Figs. 1 and 2.

The opposite ends of the side members 6, 7 are provided with aligned holes 14, 15 bored correspondingly with the holes in the members 10, 11, and the separated ends of the 95 members 6, 7 are spaced far enough apart to receive between them the opposite end of a corresponding link or of one of the links 4 which, as shown in Fig. 1, are provided with tubular portions 16. From the foregoing it 100

will be understood that the members 6, 7 diverge somewhat toward their separated ends so that the opposite end of the link is narrow enough to be fitted to an adjoining link in the manner described.

- 5 The upper marginal portions of the members 6, 7 are connected by a flat plate 17 which is integral therewith, and extends over the intermediate portion of the link, and beyond the inner side margin thereof, as shown in Figs. 1 and 3, so that it forms an extended support for the end portion of a cross-slat 18. These cross-slats are usually made rectangular in cross-section, and therefore the lower surface 10 of the slat rests squarely on the upper surface of the plate 17, to which it is secured preferably by a rivet 19 which passes vertically through the slat and through said plate, as shown in Fig. 2. It will be understood, of course, that two of the above described chains 15 are used, and that they are provided with similarly located links 5 so that the several cross-slats 18 have their ends similarly secured to the two chains.
- 20 In order that the power transmitted to the cross-slats by the chains shall not be transmitted through the rivets 19, which as has been explained would tend to cause splitting of the slats, I provide the links 5 with pockets 25 arranged to receive the ends of the slats telescopically. This is accomplished by providing said links with side walls 20, 21 at the opposite transverse margins of the plate 17 which constitutes the bottom of the pocket. 30 These side walls rise from the plate 17, and at their upper ends are provided with securing means in the forms of lips 22, 23, respectively, which are bent toward each other so that they lie substantially in a plane parallel with the plate 17, thus forming a rectangular pocket. 35 Preferably the lower portions of the side walls 20, 21 extend the full length of the plate 17, but the lips 22, 23 are made somewhat narrower, as shown in Fig. 1, thereby reducing the weight of the link. This locates the 40 greater part of the pocket beyond the inner margin of the link, and leaves the extreme end of the slat exposed from above, so that it can easily be riveted to the plate 17. The 45 dimensions of the pocket are such that it is adapted to receive the end of the cross-slat snugly, and after the slat has been put in place the lips 22, 23 may be bent down to engage the slat closely, thereby holding it firmly 50 even though the rivet 19 should become loose. 55 As shown in Fig. 1, the lips 22, 23 are not connected with each other, which arrangement is to accommodate the variations that occur in the size of the slats.
- 60 From the foregoing description it will be seen that the end portions of the slats are substantially surrounded by the side walls 20, 21 and lips 22, 23, which are integral with the driving members 6, 7 of the link. Consequently, 65 the driving power is not transmitted

to the slats by the rivets 19, and there is no danger of splitting on that account. Furthermore, the pockets hold the slats firmly enough so that even though they should split from other causes, or should be broken at some intermediate point, the end portions of the slats would nevertheless be held by the links to which they were connected, and therefore would not be carried into the machinery. The use of the rivets is desirable to aid in holding the slats against endwise movement and also in holding the ends of a broken slat in the pockets, but the use of the rivets is not essential as other means could be employed for holding the slats against endwise movement, such, for instance, as bending the lips 22, 23 down far enough to cause them to be embedded in the slats, or to engage recesses in them provided for that purpose. While I prefer to provide each of the side walls with lips 22, 23, my invention also contemplates providing only one of such side walls with a lip.

What I claim as my invention and desire to secure by Letters Patents, is—

1. An endless conveyer comprising parallel chains, and cross-slats connecting said chains, each of said chains having links composed of spaced members provided with a box-like pocket at their upper sides, each of said pockets being composed of a transverse plate integral with said members, on which the slat rests, side walls rising from said plate, and lips extending from the upper margins of said side walls inwardly over the slat.

2. A chain link comprising a driving element adapted for connection with adjoining links, said driving element having a pocket at its upper side adapted to receive the end of a cross-slat, said pocket comprising transversely disposed rigid side walls rising from said driving element, and a horizontally disposed bendable lip extending from the upper margin of one of said side walls over said pocket.

3. A chain link comprising a driving element composed of spaced members connected together at one end and adapted to be connected with adjoining links, a pocket at the upper side of said members and integral therewith, said pocket comprising a bottom plate connecting said members, and transversely disposed side walls rising from said bottom plate provided with downwardly bendable securing means extending over the pocket.

4. An endless conveyer comprising parallel chains, cross-slats connecting said chains, and means for securing said cross-slats to said chains, each of said chains having links composed of spaced members provided with a box-like pocket at their upper sides, each of said pockets being composed of a transverse plate integral with said members, on which the slat rests, side walls rising from said plate,

and lips extending from the upper margins of the inner portions of said side walls inwardly over the slat, leaving the outer portion between said side walls open for receiving the means for securing said slat to said transverse plate.

5. A chain link comprising a driving element adapted for connection with adjoining links, said driving element having a pocket at 10 its upper side adapted to receive the end of a cross-slat, means for securing the end of said slat in said pocket, said pocket comprising transversely disposed rigid side walls rising from said driving element, and a horizontally 15 disposed bendable lip extending from the upper margin of the inner portion of one of said side walls over said pocket, leaving the outer portion between said side walls open for receiving the means for securing said slat in 20 said pocket.
